DESIGN FOR A COMBINED READING STAND AND LAMP

Frank J. Luketa, Seattle, Wash.

Application March 26, 1946, Serial No. 127,960

Term of patent 14 years

(Cl. D33—10)

To all whom it may concern:

Be it known that I, Frank J. Luketa, a citizen of the United States of America, residing at Seattle, in the county of King and State of Washington, have invented a new, original, and ornamental Design for a Combined Reading Stand and Lamp, of which the following is a specification, reference being had to the accompanying drawing, forming part thereof.

I claim:

The ornamental design for a combined reading stand and lamp, substantially as shown.

FRANK J. LUKETA.
